UNITED STATES PATENT OFFICE.

COY GEORGE, OF BLYTHEVILLE, ARKANSAS.

INTERNAL-COMBUSTION ENGINE.

Application filed August 3, 1920, Serial No. 400,993. Renewed August 9, 1922. Serial No. 580,811.

To all whom it may concern:

Be it known that I, COY GEORGE, a citizen of the United States, residing at Blytheville, in the county of Mississippi and State 5 of Arkansas, have invented new and useful Improvements in Internal-Combustion Engines, of which the following is a specification.

This invention relates to internal combustion engines and comprehends the construction making use of a stationary piston arranged within a sleeve connected with the crank shaft for reciprocatory movement within the cylinder, the sleeve being designed to provide compression and firing chambers at its opposite ends, whereby every stroke is a power stroke, thus providing for compactness, less floor space and a motor which will develop as much power as a two 20 cylinder two cycle engine.

Another object of importance resides in the provision of a construction, wherein the piston is cooled by water circulation, the water passing through the piston pin which 25 is in open communication with the water jacket, means being also devised to allow for the escape of air from the piston.

The nature and advantages of the invention will be better understood when the following detailed description is read in connection with the accompanying drawings, the invention residing in the construction, combination and arrangement of parts as 30 claimed.

5 In the drawings forming part of this application, like numerals of reference indicate similar parts in the several views, and wherein:—

Figure 1 is a side elevation of the engine 40 partly in section.

Figure 2 is a vertical sectional view taken at right angles to Figure 1.

Figure 3 is a view in elevation of the piston removed.

45 Figure 4 is a similar view of the reciprocatory sleeve.

Figure 5 is a view of the crank shaft.

Figure 6 is an enlarged fragmentary sectional view of a modified form of the invention.

55 Referring to the drawings in detail, 10 indicates the crank shaft of the motor, in which the cylinder 11 partly extends, the cylinder being provided with the usual water space 12. The outlet opening of the water space or jacket is indicated at 13 in

Figure 1, and the water may be drained from the jacket by means of a pet cock indicated at 14 in Figure 1. The water pump 15 is arranged at one side of the cylinder 16 and actuated from the crank shaft 17 journaled in suitable bearings 18 of the crank case, and equipped at one end with the fly wheel 19. The carbureter occupies the space indicated at 20 in Figure 1. A plurality of 60 spark plugs 21 are mounted in one side of the cylinder, there being two of these plugs for the respective firing chambers to be hereinafter described. The crank shaft 16 is provided with counterbalancing weights 22. 65

Arranged within the cylinder 11 at a point approximately midway between the ends thereof, is a stationary piston 23 supported by a pin 24 which projects beyond the sides of the piston and received by suitable 70 bearings in the cylinder. The piston is equipped with packing rings 25 and is further provided at each end with an extension 26 constituting a deflector for the gas or combustible mixture admitted to the 75 firing chambers. The piston 23 is arranged within a sleeve 27 of suitable length to define firing chambers 28 and 29 respectively in the opposite sides of the piston 23. This sleeve is closed at both ends, the upper end 80 being closed by means of a removable head 30 while the lower end 31 is positioned an appreciable distance within the sleeve 27. The sleeve 27 is associated with the crank shaft by means of a connecting rod 32 which 85 has one end arranged within the sleeve immediately beneath the lower end wall 31 and connected thereto by means of the pin 33. Vertically disposed slots 34 are provided in the sleeve to receive the pin 23 which supports the stationary piston 23. The sleeve 27 is further provided above and below the slot 90 34 with inlet ports 35 and exhaust ports 36. These ports are of course adapted to be brought into registration at the proper time 95 with the terminals of the intake manifold 37 and the exhaust manifold 38. The space within the cylinder 11 above the sleeve 27 defines a compression chamber 39, while the space within the crank case beneath the 100 lower end of the sleeve constitutes a compression chamber 40. The cylinder is formed with a passage 41 to establish communication between the compression chamber 39 and the firing chamber 28 when the sleeve 110 27 is in its uppermost position, the cylinder being further provided with a passage

42 to establish communication between the compression chamber 40 and the firing chamber 29 when the sleeve is in its lowermost position. Obviously, the inlet ports 35 of 5 the sleeve are alternately brought into registration with the respective passages 41 and 42. Similarly, the exhaust ports 36 of the sleeve alternately register with the respective terminals of the exhaust manifold 10 38. The sleeve 27 is also provided with spaced openings 43 through which the spark plugs fire at the proper intervals.

In practice, assuming that the sleeve is in the position shown in Figure 2, the burnt 15 gases exhaust from the firing chamber 28 through the manifold 38, and the combustible mixture from the compression chamber 39 enters the firing chamber 28. The combustible mixture which is conveyed from 20 the chamber 39 into the passage 41, is directed against the extension 25 which deflects the mixture upwardly in the chamber 28. When the charge now contained in the 25 firing chamber 29 is fired, it drives the sleeve 27 downwardly thus cutting off communication between the chamber 28 and the 30 passage 41, and bringing the inlet and exhaust ports 35 and 36 respectively in the lower half of the sleeve in communication with the exhaust manifold 38 and the 35 passage 42. When in this position, the burnt 40 gases exhaust from the chamber 29, while the combustible mixture is transferred from the compression chamber 40 into the firing chamber 29 through the passage 42, this mixture being directed against the projection 45 25 which deflects the combustible mixture in the proper direction and prevents it from mingling with the burnt gases which 50 are being exhausted through the exhaust manifold 38. It is of course understood, that during the down stroke of the sleeve 27, the combustible mixture is drawn into the compression chamber 39. At predetermined intervals during the down stroke of 55 the sleeve, the spark plug in the firing chamber 28, strikes the previously mentioned charge contained in the said chamber, thus driving the sleeve in an upward direction to the position which it assumes as shown in Figure 2. Manifestly, every stroke of the sleeve is a power stroke, or in other words, there are two power strokes at each revolution of the crank shaft. The engine will 60 not only develop as much power as a two cylinder two cycle engine, but the arrangement provides for compactness, the parts being readily accessible, while economy in floor space is another important feature provided for by the invention.

In Figure 6 I have illustrated a modified form of the invention wherein 50 indicates the cylinder which is provided with the usual water jacket 51. 52 indicates the piston which is the same in construction as the

piston 22 above described, the piston being arranged within the sleeve 54 a suitable length to define the firing chambers 55 and 56 respectively. The sleeve is of the same construction as the sleeve 27 above referred to. Passed through the vertically disposed slots 56' in the sleeve is a hollow pin 57 which is threaded into the water jacket as shown, the pin being provided with openings 58 adjacent the ends thereof and by means of which communication is established between the water jacket and the pin at 57. A portion of the pin is arranged within the sleeve is also provided with a plurality of openings 59 so that water may circulate 80 within the piston, the water circulation being through the water jacket and pin 57 as will be readily understood. An angularly shaped pipe including a vertical flange 59' is extended through one of the openings 58 85 of the pin vertically within the sleeve, a horizontally disposed branch 60 of the pipe being passed through the pin beyond one end thereof and is equipped with a pet-cock 90 or the like 61. The pipe is designed to occupy a minimum space, and is utilized to permit of the escape of air from the sleeve so as not to retard the circulation of water in any way. Otherwise, this form of the invention is the same as that above described.

While it is believed that from the foregoing description the nature and advantages of the invention will be readily apparent, I desire to have it understood that I do not limit myself in the details herein shown and described and that such changes may be resorted to when desired as fall within the scope of what is claimed.

What I claim is:

1. An engine comprising a cylinder, a crank shaft, a crank case, a sleeve arranged within the cylinder for reciprocatory movement, a stationary piston arranged within the sleeve, a transverse pin supporting the piston and projecting beyond the opposite sides thereof, said sleeve having elongated slots for the reception of said pin, said sleeve being closed at both ends and defining firing chambers at the opposite sides of the stationary piston, and compression chambers in the intervening space between one end of the sleeve and the adjacent end of the cylinder and the opposite end of the sleeve and said crank case, said cylinder having spaced pairs of inlet and exhaust ports, and said sleeve having inlet and exhaust ports for the respective firing chambers adapted to be alternately brought into registration with the corresponding port of the cylinder, and a connecting rod between the crank shaft and the adjacent end of the sleeve.

2. An engine comprising a cylinder, a crank shaft, a crank case, a sleeve arranged within the cylinder for reciprocatory move-

ment, a stationary piston fitted within the sleeve, a pin supporting said piston from the wall of the cylinder and passed through opposed slots in the sleeve, a removable head closing the upper end of the sleeve, said sleeve having a lower end wall slightly inset, a connecting rod between the crank shaft and the adjacent end of the sleeve, said sleeve defining opposed firing chambers at the opposite sides of the piston, and compression chambers in the space between one end thereof and the adjacent end of the cylinder and the opposite end of the sleeve and said crank case, and said sleeve having inlet and exhaust ports for the respective firing chambers.

3. An engine comprising a cylinder, a crank shaft, a sleeve arranged within the cylinder for reciprocatory movement, a stationary piston arranged within the sleeve, a hollow transverse pin terminally threaded into the water jacket of the cylinder and having openings communicating with said water jacket, said sleeve having slots for the reception of the pin, said sleeve being closed at both ends and defining firing chambers at the opposite sides of the stationary piston, said pin having other openings in its length to establish communication between the piston and water jacket whereby water is allowed to circulate within the piston, a connecting rod between the crank shaft and the adjacent end of the sleeve, and said sleeve having inlet and exhaust ports for the respective firing chambers.

4. An engine comprising a cylinder, a crank shaft, a crank case, a sleeve arranged within the cylinder for reciprocatory movement, a stationary piston arranged within the sleeve, a transverse pin terminally secured to the walls of the water jacket of the cylinder, said sleeve having elongated

slots for the reception of said pin, said pin having openings to establish communication between the water jacket and the sleeve, whereby water is allowed to circulate in the sleeve, said sleeve being closed at both ends and defining firing chambers at the opposite sides of the stationary piston, and compression chambers in the intervening space between one end of the sleeve and the adjacent end of the cylinder, and the opposite end of the sleeve and said crank case, means associated with said pin for controlling the escape of air from the sleeve, a connecting rod between the crank shaft and the adjacent end of the sleeve, and said sleeve having inlet and exhaust ports for the respective firing chambers.

5. An engine comprising a cylinder, a crank shaft, a sleeve arranged within the cylinder for reciprocatory movement, a stationary piston arranged within the sleeve, a hollow transverse pin terminally secured to the cylinder and having openings to establish communication between the water jacket of the cylinder and said pin, said pin having elongated slots for the reception of said pin, and closed at both ends defining firing chambers at the opposite sides of the stationary piston, a connecting rod between the crank shaft and the adjacent end of the sleeve, said sleeve having inlet and exhaust ports for the respective firing chambers, an angular shaped pipe having a portion arranged within the piston and a portion passed through said pin to allow for the escape of air from the piston, and a valve associated with said pipe for controlling the escape of air.

In testimony whereof I affix my signature.

COY GEORGE.
